CIRCUIT CLOSING DEVICE

Herbert F. Obergfell, River Forest, and George W. Eickenberg, Chicago, Ill., assignors, by mesne assignments, to Associated Electric Laboratories, Inc., Chicago, Ill., a corporation of Delaware

Application October 26, 1932, Serial No. 639,558

11 Claims. (Cl. 246—246)

The present invention relates in general to circuit closing devices and more particularly to a device of this type which is arranged for use in connection with railway signalling or tele-switching systems. The main object of the present invention, therefore, is to provide an improved circuit closing device or contactor which is mounted adjacent to one of the track rails and is arranged to be operated by the flanges of the wheels of the engine and the cars of a train. Such contactors are particularly useful in a railway car switching system such as disclosed in Patent No. 1,753,602, issued April 8, 1930, to Leon M. Gibbs.

Other objects and the novel features of the invention will be apparent from the following specification when read in connection with the accompanying drawings, comprising Figs. 1 to 8, inclusive, in which

Fig. 1 is a top view of the complete contactor mounted in position adjacent to a track rail;

Fig. 2 is a front view of the complete contactor as mounted on the track rail;

Fig. 3 is a side view of the complete contactor and shows the manner in which the contactor is attached to the track rail;

Fig. 4 is a front view of the casing 5 with the cover 6 removed and shows the electrical terminals and the circuit closing contacts;

Figs. 5 and 6 are cross-sectional views of the casing 5 and the cover 6 and illustrate the manner in which the cover 6 fits on the casing 5 to prevent moisture from entering the casing 5 and interfering with the proper working of the circuit closing contacts;

Fig. 7 is a cross-section of the complete contactor taken along the line 7—7 of Fig. 2; and

Fig. 8 is a face view of the block 3 with the casing 5 and the plunger assembly 30 removed therefrom, and shows the manner in which the operating rocker arm 28 is mounted in the housing 3.

Referring to the drawings, the contactor assembly is secured to the track rail by means of bolts 4 which pass through the rail and through the splice bar or joint bar 2 on the other side of the rail. The contactor assembly consists essentially of three parts, the main housing 3 which contains the operating plunger assembly, the housing or casing 5 which contains the contact assembly and the terminals, and the cover 6. The casing 5 is secured to the main housing 3 by means of bolts 12 and the cover 6 is secured to the casing 5 by means of bolts 13. The cover 6 is arranged to fit over casing 5 with a practically air tight fitting to prevent moisture from entering the casing 5 and interfering with the proper functioning of the circuit closing contacts. This is accomplished by means of the ridge or raised portion 53 which extends around the face 55 of the casing 5 and is arranged to fit into a cor-

responding groove in the cover 6. This groove contains a gasket 54 so that the fitting will be moisture proof when the cover 6 is securely bolted down to the casing 5. This fitting is clearly illustrated in Figs. 5, 6, and 7 of the drawings.

The main housing 3 of the contactor encloses the plunger 8 which is adapted to be struck by the flange of the railway car wheels. This plunger fits into a sleeve 18 within the housing 3. The plunger is hollow for a portion of its length to receive the spring 22, the other end of the spring fitting over a circular raised portion 21 in the bottom of the opening within housing 3. The sleeve 18 and the plunger 8 are retained within the housing by means of the flat ring 17 against which the shoulder of the plunger rests in its normal position. The ring 17 is held in place by means of the retaining ring 7 which in turn is held in place by screws 9 which are countersunk in the retaining ring 7. A leather washer 16 is provided around the outside of the plunger 8 and is held firmly against the surface of the plunger by means of the spring 60. The retaining ring 7 is somewhat larger than the plunger, the space between the ring 7 and the surface of the plunger being filled by the leather washer 16. This leather washer serves two purposes; namely, it prevents oil from the plunger well from being pumped out by the plunger during its operation, and it prevents the plunger from becoming locked in its operated position as is possible in case the retaining ring 7 should fit tightly against the plunger 8. This might be brought about by the rail 1 becoming worn and also a car wheel becoming worn so that the flange on the wheel becomes too long. In this case the flange of the carwheel might extend down far enough to ride over the retaining ring 7, smashing over the edge of the ring so that it extends over the plunger in its operated position and would not allow the plunger to release. This difficulty is overcome by the leather washer 16, since in case the flange on a car wheel is too long and the edge of the retaining ring 7 is bent over, this does not affect the operation of the plunger as the bent over portion merely touches the washer 16 and does not extend over the opening through which the plunger passes.

The sleeve 18 is provided with a slot 19 extending along one side of its length. A pin 61 is embedded in the housing and extends a short distance into the plunger well or opening and fits into groove 19 to serve as a guide for the sleeve 18 so that it will be properly positioned in the housing. A hole 23 and a hole 24 are bored through the sleeve into the slot 19. These holes are part of the oiling system which keeps the plunger well lubricated. A screw plug 11, 60

such as shown in Figs. 1 and 3, is provided in the housing to designate the proper oil level, and the oil may be drained from the hole in which this plug fits so that it will be at the proper level. A hole 25 is provided on the opposite side of the sleeve and a narrow slot 20 extends along the surface of the sleeve upward to the top and across the upper edge in order to provide an oil return path and also to permit free movement of air between the plunger well and the opening formed around the upper portion of the plunger when it is depressed. The operating rocker arm 28 is pivoted on a pin 29 which in turn is held within the housing by means of the two screws 10 which abut against the ends of the pin. On the lower portion of the operating rocker arm are mounted two rollers 26 and 27. With the operating arm in its normal position as shown in Fig. 7, the roller 26 extends through the hole 25 in the sleeve 18 and lies in the path of plunger 8. The roller 27 rests against the face 35 of the contact operating plunger 33.

The contact operating plunger 33 fits within a casing 39 which is secured to the main housing 3 by means of screws 32. The plunger 33 is held against the roller 27 by means of a spring 34 one end of which rests against the plunger head 35 and the other end of which rests against washers 36 which fit into the hole in the casing 39. The plunger stem extends through a hole in the casing 5 and through a slot in the contact arm 41. Insulating washer 55, a nut 43, and a lock nut 44, are provided on the end of the plunger stem so that it cannot be withdrawn through the slot in the contact arm 41. Contact arm 41 is pivoted at 42 and carries the spring 45. This spring has a knob at its lower end which rests against the wall of casing 5. The spring is then bent around the pivot point of the rocker arm 41 and retained underneath the pin 62 so that the spring pressure is attempting to force the contact arm to the left and into engagement with the stationary contact 63. This spring pressure is opposed by the spring 34 which maintains the plunger 33 in its right hand position, the plunger pulling the contact arm 41 away from the stationary contact 63. The stationary contact is mounted on a bracket 47, and is adjustable by means of the screw 48 and lock nut 49.

Also within the casing 5 is mounted the terminal assembly 50 consisting of a number of terminals comprising the nuts 51 and 52 through which the wire connections are made to the contactors. Three of these terminals are provided, one being connected to the contact arm 41, another being connected to the stationary contact 63, and the third being a spare terminal.

From the foregoing description of the structure of the contactor, it will be clear how the contactor operates. Each time a car wheel passes over the rail 1 the flange of the wheel strikes the top of a plunger 8 pressing the plunger down into the plunger well. As the plunger is forced down, the edge of the plunger strikes the roller 26 forcing it through the hole 25 to the left and rotating the operating rocker arm 28 about its pivot point 29. This forces the roller 27 against the head 35 of the plunger 33 forcing this plunger to the left. As the plunger 33 moves to the left, the spring pressure of the flat spring 45 forces the contact arm 41 to follow the plunger until the contact 41 engages the stationary contact 63 thereby closing an elec-

trical circuit. As soon as the plunger 8 is released, it is again restored to its normal position by means of spring 22 allowing the spring 34 to return plunger 33 to its normal position, thereby drawing the contact arm 41 to the right and breaking its contact with the stationary contact 63.

The contact arm 41 has been arranged to be operated by spring power instead of directly by the plunger 33. This is necessary since it was found that when the contact arm was fastened to the plunger so that the movement of the plunger to the left forced the movable contact against the stationary contact, the contact arm gradually became bent and in a short time the contacts would not close. This was probably due to the fact that when a train was travelling at great speed and the flanges of the car wheels struck the plunger 8 with great force, the plunger 33 was moved to the left with considerable speed. This caused the contacts to close with considerable force, bending the contact arm 41. As now arranged, the plunger 33 simply releases the contact arm which is moved against the stationary contact by spring power, thereby eliminating the above difficulty.

The plunger 8 is rounded at its upper end and the contactor is so designed that the flanges of the car wheels do not strike the plunger 8 in the exact center but strike the upper surfaces of the plunger to the right of its center line. This causes the plunger 8 to be rotated slightly each time it is struck by the flange of a car wheel and is forced downward to operate the contactor. When the plunger 8 is forced down into the plunger well, it operates the operating rocker arm 28, as previously described, and when the lower edge of the plunger passes the hole 25 it seals the lower portion of the well containing the oil so that as the plunger is lowered still further, the air pressure forces the oil through the hole 23 and upward in the slot 19, some of the oil being forced out of the hole 24 against the side surface of the plunger 8. As the plunger is rotated slightly each time it is operated as described above, the oil forced through the hole 24 keeps the entire surface of the plunger well lubricated. The oil and air passageway 20 is provided so that any oil which is pumped up by the plunger will not be forced out past the outer washer 16 but will be free to return to the bottom of the well through the slot 20.

Each time the plunger 8 is released after the flange of the car wheel has passed thereover, it is forced upward by means of the spring 22. As the spring 22 expands and some of its coils are forced upward out of the oil, they carry considerable oil along and this oil is splashed through the hole 25 and serves to keep the rollers 26 and 27 and the contact operating plunger 33 well lubricated. An oil vent 31 is provided to permit free flow of oil between the space occupied by the plunger stem and the spring 34 and the slot 31 which connects with the oil reservoir by means of the hole 25. This is to prevent the oil being pumped into the opening between the casing 5 and the housing 3 through the packing around the plunger stem. Thus all the moving parts of the contactor are kept well lubricated at all times and the only attention necessary is to keep the oil reservoir filled to the proper level.

An opening is provided on each side of the casing 5 to accommodate incoming electrical cables. In the contactor illustrated in the draw- 75

ings, one of these openings has been closed by plunger, a rocker arm pivoted at its upper end and having two rollers.

5 means of the screw plug 14. The other opening is provided with a strain relief bushing 15 which fits tightly around the incoming cable to prevent moisture entering the housing 5.

What is claimed is:

1. In a circuit controller for use in railway signalling systems, a plunger mounted adjacent to a track rail operated in a vertical and rotary movement by the flanges on the car wheels passing over the rail, a horizontal plunger, a pair of contacts, means responsive to the vertical operation of said first plunger for operating said horizontal plunger, and means controlled by said horizontal plunger for closing said contacts, the rotary movement of the first plunger preventing excess wear in one spot on the plunger by the car wheels. 10
2. In a circuit controller for use in railway signalling system, a vertical plunger mounted adjacent to a track rail so as to be operated by the flanges of car wheels passing over the rail, a horizontal plunger, a stationary contact, a movable contact normally held away from said stationary contact by said horizontal plunger, means responsive to the operation of said vertical plunger for operating said horizontal plunger to release said movable contact, and means for moving said movable contact into engagement with said stationary contact. 15
3. In a circuit controller, an operating plunger, a second plunger, a stationary contact and a movable contact, said movable contact normally held away from said stationary contact by said second plunger, means including a rocker arm and two rollers for imparting the motion of said first plunger to said second plunger, and means responsive to the movement of said second plunger for closing said contacts. 20
4. In a circuit controller for use in railway signalling system, a vertical plunger operated by the flange of a car wheel, a second plunger, a stationary contact and a movable contact, said movable contact normally held away from said stationary contact by said second plunger, means responsive to the operation of said first plunger for operating said second plunger to release said movable contact, and a spring for forcing said movable contact against said stationary contact. 25
5. In a circuit controller for use in railway signalling systems, a vertical plunger normally held in its upper position by spring power, a second plunger mounted horizontally, an operating rocker arm pivoted at its upper end, two rollers at the lower end of said arm, the first lying partly in the path of said first plunger and the second resting against the head of said second plunger, whereby the first plunger when forced downward by the flange of a car wheel strikes said first roller and forces said arm to swing on its pivot thereby operating said second plunger, a pair of contacts, and means controlled by said second plunger for closing said contacts. 30
6. In a circuit controller for use in railway signalling systems, a vertical plunger arranged to be operated by the flanges on the car wheels of a train, a spring for normally maintaining said plunger in its upper position, a sleeve in which said plunger slides when operated, said sleeve having a hole at one side thereof, a second 35
7. In a circuit controller, a vertical plunger, a horizontal plunger, a pair of contacts, means for operating said horizontal plunger, means including a rocker arm and two rollers for imparting the motion of said vertical plunger to said horizontal plunger, means controlled by said horizontal plunger for closing said contacts, and means effective each time said vertical plunger is operated for lubricating said two plungers and said rocker arm and rollers. 40
8. In a circuit controller, a casing, a vertical plunger mounted in said casing, a spring for normally maintaining said plunger in its upper unoperated position, a cylindrical sleeve in said casing in which said plunger slides, the lower portion of said sleeve forming a receptacle for oil, means for operating said plunger, and means for lubricating the sliding surfaces of said plunger and sleeve, said means including a passageway for oil extending through said sleeve wall, along a groove in the outer surface of said sleeve, and through the sleeve wall at a point where the plunger surface is in contact with the inner surface of the sleeve when the plunger is operated and oil is forced through the passageway. 45
9. In a circuit controller, a housing, a vertical plunger mounted in said housing, a spiral spring for normally maintaining said plunger in its upper unoperated position, a cylindrical sleeve in said housing serving as a guide for said plunger, the lower portion of said sleeve forming a receptacle for oil, said sleeve having a vertical groove in the outer surface thereof and two holes through the sleeve wall connecting the groove with the inner oil space, the first hole being below the oil level and the second hole being above the oil level, and means for operating said plunger, the operation of said plunger forcing oil through said first hole into said groove and through said second hole against the surface of said plunger thereby maintaining the sliding contact between the surface of said plunger and the inner surface of said sleeve well lubricated. 50
10. In a circuit controller for use in railway signalling systems, a vertical plunger mounted adjacent a track rail, said plunger operated by a car wheel passing over said track rail, a pair of contacts, a spring having tension normally tending to hold the contacts in normal position, another spring having tension overcoming the tension of the first spring and holding the contacts in reversed position, said plunger when operated removing the influence of the second spring to thereby render the first spring effective to move the contacts into normal position. 55
11. In a circuit controller for railway signalling systems, contact springs, a pivoted rocker arm, a plunger mounted adjacent a railway track rail in the path of car and operated by wheels passing thereover, a spring normally holding said arm in the path of said plunger and also holding said contact springs in one position, said plunger operated by a car wheel to move said arm and overcome the tension of said spring, and another spring rendered effective by the operation of said arm to operate said springs to then alternate position. 60
